Primary Examiner — Christy Nemeth(74) *Attorney, Agent, or Firm* — Harness, Dickey & Pierce, PLC(57) **CLAIM**

The ornamental design for a bracket, as shown and described.

DESCRIPTION

FIG. 1 is a left, top, rear perspective view of a bracket of my new design;

FIG. 2 is another left, top, rear perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof; and,

FIG. 8 is a bottom plan view thereof.

The dash-dash broken lines in the drawings illustrate environmental subject matter that forms no part of the claimed design. The dash-dot broken lines in the drawings illustrate a boundary and form no part of the claimed design.
